UNITED STATES PATENT OFFICE

JOHN S. ROBINSON, OF CANANDAIGUA, NEW YORK.

IMPROVEMENT IN THE TREATMENT OF PLOW MOLD-BOARDS.

Specification forming part of Letters Patent No. 177,961, dated May 30, 1876; application filed March 27, 1876.

To all whom it may concern:

Be it known that I, JOHN S. ROBINSON, of Canandaigua, in the county of Ontario and State of New York, have invented a certain new and useful Process for the Treatment of Mold-Boards of Plows and other castings; and do hereby declare that the following is a full, clear, and exact description thereof, which will enable others skilled in the art to which it pertains to make and use the same, reference being had to the accompanying drawings, and to the letters of reference marked thereon, which form a part of this specification, in which—

Figure 1 is a sectional elevation of a flask, bottom board, and chill, suitable for casting a mold-board for a plow, said board being shown in position. Fig. 2 is a plan of the bottom board, with the chill and pattern in position. Fig. 3 is a side elevation of the chill, and Fig. 4 is a perspective view of a plate of metal or other substance which is used upon the casting after the chill has been removed.

Corresponding letters denote like parts in all of the figures.

This invention relates to a process for the treatment of the mold-boards of plows and other castings, previous to their being removed from the flask or mold in which they are formed; and it consists in chilling a portion thereof, and the application to such chilled surfaces of a highly-heated piece of metal or other equivalent substance, while that portion of the casting which is upon the opposite side to that which was in contact with the chill when cast is in a plastic or semi-fluid condition, or while the casting is yet at a red heat, the object being to prevent the unequal cooling thereof and the consequent unequal shrinking and strain upon the same, as well as the change of form likely to result from such unequal cooling.

In making mold-boards of plows and treating them according to my process I use a bottom board, A, which may be of any desired form, and of any suitable substance, such as wood or metal, and of sufficient dimensions to receive upon its upper surface a flask, B, in which to place the sand. Upon this bottom-board the chill C is placed, the upper surface of which is to be of a form adapted to receive the outer surface of the mold-board, while its

lower surface is of such form as to allow it to rest upon the board, or upon the sand when no bottom board is used.

The chill C having been placed in position in the mold, the pattern D is placed thereon, as shown in Fig. 1, when sand is packed around its edges and sloped down to the bottom board, and the flask B is then filled with sand, which is tramped down upon the pattern in the usual manner. When the mold has been formed in this manner the flask may be lifted off, the pattern removed, and the chill taken out and heated to such an extent as to prevent the accumulation of any moisture thereon, and to expel any that may accumulate in the space within the mold, when the chill is returned to the mold, the flask replaced, and the metal poured in while the chill is yet warm, by which operation the metal of the lower side of the casting is brought in contact with the chill B, and is quickly set and at the same time hardened, while the metal on its opposite side will for some time remain in a plastic or semi-fluid state; and in order to avail myself of this fact, I at once turn the flask over, or to such an angle as to make it convenient to remove the chill, and to apply a highly-heated plate of metal, or other equivalent substance, to that portion of the casting from which the chill has been removed, the effect being to prevent the further rapid cooling of that surface, and thus allow all parts of the casting to cool evenly, the result of which is that when the casting is removed from its mold it retains its full strength, it not being weakened by unequal strain in cooling, or subjected to a change of form by such strain.

The plate E, which it is proposed to apply in the heated condition referred to, is shown in Fig. 4, it being supplied with handles, as shown, for convenience in handling. This plate E may be made of metal, of such material as fire-bricks are composed of, or of any material that has sufficient adhesion in its particles to admit of its being handled, and that will retain a sufficient amount of heat to produce the required effect upon the casting, and hence I do not limit my invention to the material out of which said plate is made. In order that this plate may produce the best possible effect it is important that it

should be applied as soon as possible after the surface with which it is to be placed in contact has become solidified, and while the metal upon the opposite side is still in the state described, in order that the lengths of the surfaces may not be changed by the unequal cooling of the two sides.

I have described the bottom board and the chill as consisting of separate parts, but it is apparent that they may be made of one piece of metal; or the chill may be used without any bottom board, it being placed upon the sand or floor of the foundry; but as those devices form no part of my present invention, they need not be more particularly described here.

Having thus described my invention, what I claim is—

The herein-described process for treating mold-boards of plows and other castings, it consisting in the application to the chilled surface or surfaces of such castings, of a conforming-plate of highly-heated material, while the unchilled portion is still in a plastic state, or while the whole is at a red heat, and before it has been removed from the flask or mold in which it was formed, substantially in the manner and for the purpose specified.

In testimony that I claim the foregoing as my own invention I affix my signature in presence of two witnesses.

JOHN S. ROBINSON.
